**CIRCULAR KNITTING MACHINES EQUIPPED
WITH WRAP THREAD MECHANISM**

Alfred Percy Saunders, Leicester, England, assignor to Wildt Mellor Bromley Limited, Leicester, England, a British company

Filed Jan. 22, 1958, Ser. No. 710,461

Claims priority, application Great Britain Jan. 28, 1957
9 Claims. (Cl. 66—135)

This invention relates to circular knitting machines of the superimposed needle cylinder type furnished with a vertical embroidery head, by which is meant a wrap striping mechanism comprising individually movable wrap instruments for wrapping or lapping wale or embroidery threads drawn from bobbins, pirns, spools or like individual supplies, around predetermined needles, such threads being additional to the main yarn or yarns ordinarily supplied, and means for producing relative movement between the needles and the wrap instruments for the purposes of producing wrap striping and a variety of other different design effects such, for example, as vertical or diagonal stripes, clocks, broken zig-zag effects, individual geometrical and other ornamental motifs and the like by embroidery plating on one face of knitted fabric.

The invention has reference particularly to superimposed needle cylinder knitting machines furnished with double-ended latch needles transferable from one cylinder to the other, and vice versa, and equipped with wrap striping mechanism of the now well known kind wherein wrap instruments of a circular series consist of blade-like elements each provided with a lower thread guiding extremity, which instruments are arranged so as to extend in an axial direction or substantially so with respect to the needle cylinders and are adapted for movement radially for the purpose of carrying their wale threads across the needle circle, from the inside to the outside and vice versa, by virtue of which movement and conjoint relative lateral movement between the thread guiding extremities and the adjacent hooked ends of the needles which are to receive the threads, the latter are wrapped or lapped around desired needles. For convenience in the following further description such a mechanism will hereinafter be referred to as "a wrap striping mechanism of the kind herein referred to."

In a wrap striping mechanism of this kind, a typical example of which is disclosed in the specification of prior Patent No. 2,065,469, each of the wrap instruments is provided with a thread guiding extremity at least a portion of which extends at an angle, for example at right angles, from the main portion of the blade, and the said instruments are mounted in a longitudinally tricked cylindrical bed, located concentrically with the top cylinder of the machine, for individual movement radially conjointly with the aforementioned relative lateral deflection between the instruments and the corresponding needles for wrapping purposes. Usually, although there is no limitation in this respect, the wrap instruments are adapted to be deflected laterally in relation to and as the result of engagement with corresponding needles. To this end each wrap instrument may have its lower thread guiding extremity laterally offset, e.g. bent, cranked or twisted, so as to enable it to co-operate with an adjacent needle suchwise that deflection of the instrument is effected simply as the result of the co-action of the laterally offset extremity with the adjacent needle during radial movement of the instrument. The formation of each wrap instrument in this case is such that when projected radially outwards at its thread guiding lower end it holds its wale thread in a favourable position for engagement by a needle, and upon retirement this end yields laterally when passing the said needle, resuming its normal position when fully retracted

radially inwards so that the thread is passed around the front of the needle below the hook thereof whereupon the needle can form the said thread into an embroidery stitch appearing on the face of the fabric. Lateral deflection of the lower extremities of the wrap instruments, in a wrap striping mechanism of the kind herein referred to, may alternatively be effected as the result of relative movement between the instrument and corresponding separate deflecting elements.

10 In a wrap striping mechanism of the kind herein referred to, moreover, the wrap instruments of the circular series are mounted for pivotal or rocking movement in their cylindrical bed, and are adapted to supply their wale threads each to a single needle or each to two or 15 more needles, if desired. The wrap instruments have their lower extremities (in which wale thread guiding holes are formed) normally located within the circle of needles to which the threads are supplied, and these extremities are swung first outwards and then inwards upon 20 selection of the instruments to wrap.

It is primarily the intention to apply the invention to circular superimposed needle cylinder hose or half hose machines.

The primary object of the present invention is to provide, in a wrap striping mechanism of the kind herein referred to, improvements whereby the wrap instruments are subject, throughout all their movements, to complete and positive control.

A further object of the invention is to provide for such 30 wrap instruments a simple and efficient control system which is adjustable to compensate for needle hooks of different sizes, i.e. differences in needle gauge.

Another object is to provide a wrap instrument control system designed to enable instruments which are not required to wrap needles to remain quiescent, the aim being, by prevention of radial movements of non-selected wrap instruments, to substantially reduce the possibility of needle breakage.

A still further object of the invention is to provide, in 40 a cam system for positively controlling the wrap instruments, improved means for automatically drawing or measuring off the wale threads and thereby enabling needles to take sufficient slack thread to permit of the production of clear and bold plated stitches.

Another object is to provide, for use in a superimposed 45 needle cylinder machine equipped with wrap striping mechanism of the kind herein referred to, a generally improved form of wrap instrument, as will be hereinafter described.

Yet another object of the invention is to provide simple and efficient means for neutralizing selections of the wrap instruments as and where required. In this regard, for example, and in connection with a seamless hose or half hose machine, it may be desired to make an "all around" selection of the wrap instruments for ornamenting a leg and then, without in any way disturbing the pattern set out, to neutralise, i.e. render inoperative, selected instruments in substantially one half of the series so that "half round" patterning proceeds in the instep only during knitting of the foot of the article being produced. 55 Similarly, of a succession of wrap instruments selected to execute wrapping motions, groups of such instruments may be neutralised during the production of, say, small embroidery plated areas.

A further aim is to provide in a machine of the type concerned two different system for the selective wrapping of needles the adoption of which systems, in combination, safely increases the embroidery patterning scope of the machine as will be hereinafter described.

In accordance with the essential feature of this invention, which enables the aforementioned aims and objects to be achieved, the wrap instruments in a wrap striping

mechanism of the kind herein referred to embodied in a circular knitting machine of the superimposed needle cylinder type, are normally disposed at a first and inoperative height at which they are quiescent and maintained inoperative with their thread guiding extremities withdrawn, and are adapted to be displaced lengthwise to a second and operative height at which actuating butts thereon are disposed in the range of a control cam system whereby movements of such displaced instruments are completely and positively controlled during the wrapping of wale threads around desired needles.

In one arrangement, the wrap instruments are adapted to be individually selected and displaced lengthwise from the first, i.e. inoperative height to the second, i.e. operative, height so that the thread guiding extremities of selected instruments only will be moved radially to and fro across the needle circle whilst the remaining non-selected instruments are quiescent with their thread guiding extremities withdrawn, and means are provided for moving to a common wrap level all the needles of a group or succession of needles requiring to be selectively wrapped so that desired ones of such needles can receive wale threads from the selected wrap instruments.

In an alternative arrangement there are provided means for moving all of the wrap instruments of at least one group of succession en bloc from the first, i.e. inoperative, height to the second, i.e. operative, height so that the thread guiding extremities of all the instruments of the said group or succession will be moved to and fro radially across the needle circle, and means for moving to a wrap level only selected needles of a corresponding group or succession whereby only these selected needles will receive wale threads from wrap instruments, the non-selected needles of the said group or succession remaining at another level clear of the instruments.

As will be hereinafter described in more detail it is within the scope of the invention to provide at respectively different wrapping stations the two systems of selection defined in the last preceding two paragraphs.

In order that the invention may be more clearly understood and readily carried into practical effect, a specific example thereof will now be described with reference to the accompanying drawings, wherein,

FIGURE 1 is a vertical sectional view of so much of a circular hose or half hose knitting machine as is necessary to illustrate the application of the present invention thereto.

FIGURE 2 is a detail vertical sectional view showing one of the wrap instruments in its inoperative position, that is to say at the first or inoperative height at which the lower thread guiding extremity of the instrument is withdrawn within the needle circle,

FIGURE 3 is another view similar to FIGURE 2 but depicting the wrap instrument moved up to the second and operative height at which its actuating butt is in the range of the control cam system, the instrument being shown with its thread guiding extremity projected to the outside of the needle circle,

FIGURES 4, 5 and 6 are three fragmentary views of the upper portion of a wrap instrument shown firstly at the said inoperative height prior to selection, then secondly at the operative height after selection but prior to being rocked by the control cam system for wrapping, and thirdly rocked to project its thread guiding extremity outwardly,

FIGURE 7 is a sectional plan view taken on the line VII—VII of FIGURE 1 illustrating the control cam system for the wrap instruments.

FIGURES 8 and 9 are further sectional plan views taken on the lines VIII—VIII and IX—IX of FIGURE 1 respectively, showing apertures or gaps formed in rotary parts co-axial with and located above the top cylinder component, these apertures or gaps facilitating the withdrawal of wrap instruments upwardly from the machine as occasion demands, and

FIGURE 10 represents in diagrammatic fashion a developed lay-out of the complete cam systems.

Like parts are designated by similar reference characters throughout the drawings.

Referring to FIGURE 1 it will be seen that the two-feed circular hose or half hose knitting machine therein illustrated includes a rotary bottom or plain needle cylinder 1, a rotary co-axial top or rib needle cylinder 2, double-ended latch needles such as 3 for operation in these cylinders, and bottom and top sliders 4 and 5 in the cylinders 1 and 2 respectively for actuating the needles and transferring the same from one cylinder to the other, and vice versa, according to knitting requirements.

The machine is furnished with a vertical embroidery head comprising a circular series of individually movable wrap instruments 6 mounted in a longitudinally triced cylindrical bed 7 located concentrically within the top needle cylinder 2.

As shown more clearly in FIGURES 2 and 3, each of the wrap instruments 6 in this particular example consists of a blade having a lower thread guiding extremity 8 comprising an outwardly extending portion 8a at right angles to the said blade and a downwardly extending laterally bent portion 8b formed with holes 9 for the guidance of a wale thread, an actuating butt 10 of inverted L-form at the upper extremity of the blade, said actuating butt comprising a vertical portion 10a and a rearwardly directed horizontal lip 10b, a rounded fulcrum formation 11 intermediate the thread guiding extremity 8 and the actuating butt 10, and a lower butt 12 projecting from the front edge of the blade at a location immediately above the fulcrum formation 11.

To enable the wrap instruments 6 to be selected and longitudinally displaced upwardly from a first and inoperative height H (see FIGURE 2) at which they are quiescent and inoperative with their thread guiding extremities 8 withdrawn, to a second and operative height H' (see FIGURES 1 and 3) at which the actuating butts 10 are displaced in the range of a control cam system C 40 whereby the instruments are positively controlled during needle wrapping, the said instruments may conveniently be contrastingly formed, e.g. differentiated, from each other by reason of the formation, number or disposition of selecting butts thereon. Thus, in the specific example illustrated, each of the wrap instruments 6 has projecting from the front edge of the blade, at a point or points between the fulcrum portion 11 and the actuating butt 10, a triangular selecting butt or butts 13 of saw-tooth form.

The rotary bottom cylinder 1 is surrounded in the usual way by a stationary bottom cam box 14 which carries the cams of the plain cam systems for operating the bottom needle-actuating sliders 4 at the main and auxiliary feeds F and F' respectively. The rotary top cylinder 55 2 is similarly surrounded by a stationary top cam box 15 housing the cams of the rib cam systems at the said two feeds. Thus, as shown in FIGURE 10, the forward and reverse plain stitch cams at the main or front feed F are indicated at 16 and 17 respectively, whilst the rib stitch cam at this same feed is indicated at 18. The opposed plain and rib stitch cams at the auxiliary or side feed F' are shown at 19 and 20 respectively. The latch guards at the two feeds are indicated at 21 and 22 (see FIGURES 3, 7 and 10). In lieu of a top cylinder verge, the machine is equipped with a circular series of top sinkers 23 which are controlled by a sinker cam system 24 supported by the inner portion of the top cam box 15.

A needle wrapping station W immediately precedes the knitting station at the main feed F, whilst a second 70 wrapping station W' similarly precedes the knitting station at the auxiliary feed F'.

For action upon the contrastingly formed wrap instruments 6 selectively at a selecting station S, immediately in advance of the wrapping station W, for the purpose of 75 raising selected instruments from the inoperative height H,

to the operative height H' as aforesaid, there is provided a bank of selectors 25 (FIGURES 1 and 10) adapted to be rendered operative and inoperative under the control of any suitable pattern unit, such, for instance and as shown, as an intermittently rotatable pattern drum 26 fitted with pre-arranged pins 27. Alternatively, the pattern unit may take the form of a chain; or a jacquard band or equivalent. The selectors 25 may be actuated either directly by or indirectly from the pattern unit.

As previously mentioned, in the illustrated arrangement the front, i.e. outer, edges, of the wrap instruments 8 are formed with triangular selecting butts 13 of saw-tooth form disposed at different levels according to patterning requirements, and the operative ends of the selectors 25 of the bank are provided with inclined surfaces 25a for action on the said butts suchwise as to effect the required lengthwise displacement of the selected instruments. In practice, each of the wrap instruments 6 would be initially formed with a full complement of frangible selecting butts 13, and certain butts of each of the instruments would be broken away, according to requirements.

The wrap instruments pivot or rock about their fulcrum formations 11 when being moved radially back and forth across the needle circle, and it is for this reason that the selecting butts 13 are formed on the upper portions of the blades extending between the fulcrum formations 11 and the actuating butts 10. Incidentally, it is convenient here to mention that in the case of a knitting machine equipped with two (as shown) or more feeds, a needle wrapping station preceded by a bank of wrap instrument selectors and an associated pattern unit may, if desired, be provided in conjunction either with each such feed or with each of at least some of them, as the case may be and according to embroidery patterning requirements.

The second height H' to which wrap instruments are selectively moved lengthwise is, in the illustrated example, disposed above the first height H in which instance the action of selectors 25 on the selecting butts 13 serves to lift the wrap instruments 6 and thereby raise their actuating butts 10 from an inactive or lower level h to a higher level h' at which they are disposed in the range of the wrap instrument control cam system C (see FIGURES 2-6).

The first height H at which the wrap instruments 6 are normally quiescent is determined, and maintained at required times, by the engagement of the lower butts 12 with the top surface of a horizontal levelling cam 28. This levelling cam 28, preferably of ring form and extending right around the machine, is, as illustrated in FIGURE 1, supported by an upstanding portion 29a of the conventional top plate 29 which serves, inter alia, to carry the top cam box 15. The levelling cam 28 is clearly depicted in developed form in FIGURE 10.

Now the wrap instruments 6 in the arrangement so far described are individually selected at S and moved lengthwise from the first height H to the second height H' in advance of the wrapping station W so that the thread guiding extremities 8 of selected instruments only will be moved radially to and fro across the needle circle, whilst the remaining non-selected instruments are quiescent with their thread guiding extremities withdrawn. Thus, in conjunction with this system of selection (for convenience referred to as system A), it is necessary for all the needles 3 of a group or succession of needles, requiring to be selectively wrapped to be moved to a common wrap level L (FIGURE 10) at which the relevant needles can receive wale threads from the selected wrap instruments. Conveniently for this purpose a cam 30 located in the bottom cam system at the wrapping station W acts on the butts 31 of the bottom sliders 4 to position the corresponding needles at the wrap level L which is just below the normal running height of needles in the bottom cylinder 1.

But to achieve the same result it is also within the scope of the present invention to move all of the wrap instruments 6 of at least one group, or a succession of such instruments, en bloc from the first height H to the second height H' so that the thread guiding extremities 8 of all of these instruments will be moved to and fro radially across the needle circle, in which instance only selected needles of a corresponding group or succession will be moved, e.g. raised, to the wrap level, the non-selected needles of the said group or succession remaining at another level clear of the instruments. Thus, whilst in this alternative system of selection (referred to as system B), all of the wrap instruments of the group or groups or the succession concerned will have wrapping movements imparted thereto only those of the instruments adjoining needles selectively moved to the wrap level will in fact, function to wrap. Now whilst, in the specific example illustrated, the system of selection A is adopted at the selecting station S in advance of the wrapping station W associated with the main feed F, the alternative system of selection B is used at a selecting station S' in advance of the second wrapping station W' associated with the auxiliary feed F'. As will be seen in FIGURE 10, all the wrap instruments 6 of the group or succession concerned are, at the selecting station S', advanced from the first and inoperative height H to the second and operative height H' by a raising cam 32 of the bolt type adapted for action on the lower butts 12 of the instruments. As will be appreciated, this raising cam 32 replaces a bank of individually movable selectors such as those indicated at 25 at the selecting station S. The needle selecting mechanism provided at the station S' for raising only selected needles to the wrap level L may conveniently comprise selectively operable needle-raising jacks such as 33 (FIGURE 1) or 33' (FIGURE 10) arranged below and for action on the bottom sliders 4, and a bank of selectors 34 (FIGURE 1) or 34' (FIGURE 10) for action respectively on butts 35 or 35' on said jacks, the said selectors being adapted to be rendered operative and inoperative under the control of a pattern unit such as the drum indicated at 36 in FIGURE 1 and omitted from FIGURE 10. These two alternative forms of needle selecting mechanism illustrated in FIGURES 1 and 10 are both quite well known and do not require to be described in any further detail.

A feature of the invention accordingly, resides in the adoption of the two systems of selection A and B in conjunction with respectively different wrapping stations. But whereas in the particular arrangement illustrated in the drawings, applied to a two-feed machine, the system A is employed in conjunction with the wrapping station W preceding the main feed F and the system B is employed in conjunction with the wrapping station W' preceding the auxiliary feed F', it is nevertheless to be clearly understood that systems A and B may be variously employed at a plurality of stations in relation to one or more feeds.

The advantages of adopting both systems of selection A and B in one and the same machine are economy in space and an increase in the patterning scope of the machine. Thus, whilst for carrying into practice the system A at a wrapping station the necessary bank of wrap instrument selectors and the associated patterning drum are located fairly high up on the machine, i.e. immediately above the top plate thereof, a needle selecting mechanism suitable for use when carrying out the system B at another wrapping station can be provided at a much lower level, e.g. on the conventional bottom plate of the machine (see the plate 37 in FIGURE 1). This possibility of providing patterning units at different levels accordingly makes for greater flexibility in machine design, and permits the units to be suitably grouped about the knitting head of the machine in a manner conducive to maximum economy of space.

It is to be clearly understood that whilst, merely for convenience in illustration in FIGURE 1, the two pattern

drums 26 and 36 are shown one above the other on approximately the same axis, in practice these two drums would be separated circumferentially.

In FIGURE 10, the cam indicated at 38 is provided for action upon the upper butts 39 of the jacks 33' for the purpose of depressing the latter to their normal inoperative level ready for reselection.

At any appropriate point beyond the or each needle wrapping station wrap instruments raised to the second height H' and whose actuating butts have passed through the wrap instrument control cam system C at that station may automatically be restored to the first and inoperative height H for re-selection in advance either of the same, or of the next, wrapping station, as the case may be. Thus, in the illustrated example there is provided beyond each of the two wrapping stations W and W' and a little above the leveling cam 28, a return cam 40 adapted to act upon and depress the lower butts 12. That is to say, each return cam 40, by action on the upper edges of these lower butts 12, presses the latter down until their lower edges rest once again on the upper horizontal surface of the levelling cam 28.

The or each such return cam 40 for lowering wrap instruments from the second height H' to the first height H may, if desired, be of the bolt type and be withdrawable to an inoperative position as occasion demands.

For maintaining the thread guiding extremities 8 of the wrap instruments 6 withdrawn on the inside of the needle circle whenever these instruments are quiescent at the first and inoperative height H , there may be provided, at a level below the or each wrap instrument control cam system C, a circumferentially extending retaining cam 41 (see FIGURES 4 and 10) arranged to press on the backs of the actuating butts 10 of the said instruments.

The wrap instrument control cam system C at the or each needle wrapping station comprises opposed inner and outer cams or/and suitably profiled cam parts such as 42 and 43 arranged in a common horizontal plane with a space 44 between them, this space constituting, as shown more clearly in FIGURE 7, a cam track of a width sufficient to accommodate the upright portions 10a of the actuating butts 10.

In the specific illustrated arrangement, the said opposed inner and outer control cams and cam parts at each of the wrapping stations W and W' are in a horizontal plane spaced immediately above a gap 45 (see FIGURE 10) in the circumferentially extending retaining cam 41 provided for maintaining the thread guiding extremities 8 withdrawn as aforesaid.

A leading portion 42a of the inner cam part 42 of the wrap instrument control cam system C at each wrapping station is bevelled or similarly formed to avoid the rearwardly directed horizontal lips 10b of selectively raised wrap instruments 6 and the latter are lifted by selectors 25 to land these lips on to the top of the outer marginal edge portion of the said inner cam part 42. Engagement of the underside of the rearwardly directed lips 10b with the top surface of the inner cam part 42 therefore determines the second or operative height H' to which selected instruments are raised (see FIGURE 3). Opposing an inwardly shaped edge portion 42b of the profiled inner cam part at each wrapping station is a separate radially adjustable cam 43 (FIGURE 7) of inwardly directed pointed form which, by action on the fronts of the upright portions 10a of the actuating butts 10, presses the upper ends of the wrap instruments 6 radially inwards and accordingly rocks the instruments suchwise as to project their thread guiding lower extremities 8 outwardly across and to the outside of the needle circle. When projected outwardly in this way the wrap instrument extremities 8 enter an aperture 44 in the relevant latch guard 21 or 22. The apex 43a of the pointed cam 43 corresponds to the wrapping position, and the cam is radially adjustable to vary within precise limits the extent of the outward swing of the thread

guiding extremities 8 of selected instruments. By appropriate adjustment of the cam 43, it is possible to compensate for needle hooks of different sizes, i.e. having different dimensions from front to back.

Immediately adjoining the inwardly shaped portion 42b of the inner cam part 42, the latter is formed with an outwardly curved or inclined edge 42c which, by action on the backs of the upright portion 10a of the actuating butts 10, presses the upper ends of the instruments outwards again and so withdraws the thread guiding extremities 8 radially inwards from the outside to the inside of the needle circle. As will be appreciated, the outward and inward radial movements of the thread guiding extremities 8 are, therefore, measured and completely and positively controlled by the cam system C.

The wrap instrument control cam system C at the or each appropriate wrapping station, preceding a feed may, in accordance with a further feature of the invention, incorporate an approximately shaped wale thread draw-off cam (not shown) which is adapted, by suitable action on the actuating butts 10, to vary the distance between the thread guiding extremities 8 of selected wrap instruments and associated needles 3 which have been wrapped with wale threads as these needles are retracted to knocking-over position by a stitch cam at the feed. The purpose of these further movements of the wrap instruments, subsequent to a wrapping operation, and during knitting of the relevant wale threads together with ground yarn on the wrapped needles, is to enable measured lengths of such wale threads to be fed to the needles. In this way wale threads are drawn and measured off from their supplies, e.g. bobbins or the like and permitted to run slack in the region of the knitting location thereby enabling appropriate needles to draw upon the threads so measured off and slackened in the formation of embroidery stitches. The slackened wale threads result in the production of clear and bold embroidery pattern or ornamental effects in so far as burying of the wale thread stitches beneath the ground loops is prevented. The provision of a simple draw-off cam within a cam control system as just described is a great improvement upon eccentrically mounted wale thread draw-off means such as those hitherto provided above the embroidery head of a superimposed needle cylinder machine. Such a draw-off cam, unlike eccentrically mounted draw-off means mounted above the head, does not in any way interfere with the general accessibility of the upper parts of the machine.

Preferably, the or each wale-thread draw-off cam, when provided, is adjustable suchwise as to enable the extent of the slackening of the threads to be precisely varied within reasonably fine limits.

The cam part 42 and the opposed cam 43 forming the wrap instrument control cam system C at the or each wrapping station and also the circumferentially extending retaining cam 41 are provided upon carrier brackets or supports such as 49 attached to the underside of a centrally bossed portion 45a of an upper plate 45 which, in the improved machine is provided well above the conventional "top" plate 29 to support gearing employed for driving the cylindrical instrument bed. The wale thread bobbin carrier 46 is also supported from the upper plate 45.

Means may be provided for neutralising, i.e. nullifying, 65 selections of the wrap instruments as and where required. Thus, in FIGURE 10 there is shown immediately beyond the bank of selectors 25 preceding the wrapping station W and also immediately beyond the raising cam 32 preceding the wrapping station W' a neutralising cam 47 of the withdrawable bolt type, arranged to act on and depress the lower butts 12 of predetermined raised wrap instruments 6 for the purpose of restoring such instruments from the operative height H' to the inoperative height H , before the actuating butts 10 of these 70 instruments enter the cam track 44 of the relevant con-

trol cam system C. Consequently, the front butt 12 of each neutralised wrap instrument is pressed down on to the upper surface of the levelling cam 28 so that the actuating butt 10 of the said instrument passes idly beneath the came part 42 and the cam 43 of the control system C.

But to enable selectors to be neutralised in this way, the outer edge of the inner cam part 42 of each control cam system C requires to be notched or gapped as at 48, the FIGURES 7 and 10, suchwise as to provide a clear opening through which the rearwardly directed lips 10b at the upper extremities of the relevant instruments 6 can freely move downwards. That is to say, the lips 10b pass down through the cam system C from a height above to a lower height beneath the same.

In the case of the seamless hose or half hose machine illustrated, the lower butts 12 on substantially half of the wrap instruments are made shorter than those on the remaining half. Thus, those wrap instruments associated with the instep group of needles may have short lower butts 12' (FIGURE 10 right-hand side) whilst the remaining instruments associated with the foot bottom group of needles have long lower butts 12 the neutralising cam 47 preceding each of the wrapping stations W and W' being so dimensioned that, when in operation, it will act on the long and miss the short butts. By these means, and the simple expedient of rendering operative the neutralising cams 47 a change can be made from "all round" embroidery patterning in the foot without disturbing the layout of the selecting butts 13 and the operation of the selectors 25 and pattern unit 26. In these circumstances all that is necessary to enable "all round" patterning to be resumed, when required, is to effect withdrawal of the neutralising cams 47 to their inoperative positions.

By providing lower butts 12 of more than two different lengths and suitably operating the neutralising cams 47, under suitable control, it would be possible for groups of selected wrap instruments to be neutralised, thereby enabling patterning to be confined to limited areas of the knitted fabric.

The wrap instruments 6 may be arranged so that each supplies it wale thread invariably to the same needle. It is, however, preferred to make provision for varying the relative positions of the wrap instruments 6 and the needles 3 laterally so that said instruments can supply threads to different needles. This result may advantageously be achieved by displacing the wrap instruments laterally over one or more of the needles. Such displacement is, of course, effected by shogging the cylindrical bed 7 in which the wrap instruments are mounted. Shogging mechanism functioning to shog the bed 7 one or more times in one direction or the other to an extent equal to the pitch of the needles may be of the same general character as that described with reference to FIGURES 12-14 of the drawings accompanying the specification of Patent No. 2,065,469.

As shown in FIGURE 1, the upper end of the top needle cylinder 2 has rigidly attached thereto a bearing plate 50 which seats upon the balls of a ball bearing 51 carried by the conventional "top" plate 29. The internal surface of the lower portion of the top needle cylinder is somewhat outwardly bevelled or flared at 2a to provide space for accommodation of the lower ends of wrap instruments 6 whenever these are moved radially outwards across the needles in the bottom needle cylinder 1.

Secured by screws to the underside of the bearing plate 50 is a concentrical top cylinder gear 52 arranged in mesh with a pinion 53 keyed to a vertical driving shaft 54 adapted to be driven from the conventional bottom needle cylinder gear 55. This vertical shaft 54 is the standard component serving to connect the top and bottom cylinders and to drive the same together at the same rotational speed.

The cylindrical wrap instrument bed 7 extends above the top needle cylinder 2 and the latter and the said bed 75 2 and 3.

are so arranged as to provide between them an annular space 56 designed to facilitate withdrawal of wrap instruments 6 upwardly from the machine, as described in the specification of our co-pending application No. 710,216 filed January 21, 1958 and now U.S.P. 2,956,425. The rounded fulcrum formation 11 of each wrap instrument is of such dimensions as to bridge this space 56. That is to say, the front and back edges of such a rounded or ball-shaped fulcrum formation 11 make contact with the internal surface of the top needle cylinder 2 and the back of a trick 7a formed in the cylindrical instrument bed 7 respectively.

Secured to the upper end of the cylindrical instrument bed 7 by means of screws, is a gear 57 of the same diameter as the top cylinder gear 52. Below the circular series of spur teeth on the gear 57 is an outwardly extending and horizontally disposed peripheral flange 57a to the underside of which is secured a ring 58 arranged to seat upon a circular series of balls 59 of a further ball bearing 60—this time housed in a central recess 61 formed in the upper horizontal plate 45. For driving, and shogging when required, the cylindrical wrap instrument bed 7 there is provided a pinion 62 which is freely mounted on the vertical shaft 54 and is arranged in mesh with the gear 57. The wrap instrument bed pinion 62, which is of the same diameter as the pinion 53 meshing with the top cylinder gear 52, as in association therewith a driving member 63 which is keyed on the vertical shaft 54 but is adapted for axial adjustment automatically and to act between screws 64 on pinion 62 for the purpose of imparting independent turning movement to the latter as well as driving it so that the cylindrical wrap instrument bed 7 is shogged one or more times in one direction or the other to an extent equal to the pitch of the needles 3. The shogging mechanism, the details of which do not immediately concern the present invention, is, in fact, of the character described in prior Patent No. 2,065,469 aforesaid to which reference may be made for further particulars.

The wale threads, in this example, are supplied to the wrap instruments 6 from a number of bobbins or the like (not shown) supported by the carrier 46 which is arranged co-axially with respect to the cylindrical wrap instrument bed 7. This carrier 46 is mounted upon an annular bearing plate 65 which seats upon a third circular series of balls 66 of a bearing 67 accommodated in a support D rigid with and projecting upwardly from the upper plate 45. Secured to the underside of the annular bearing plate 65 is a bobbin carrier gear 68 of the same diameter as the gears 52 and 57, and this bobbin carrier gear 68 also meshes with a pinion 69 keyed to the vertical shaft 54. The pinion 69 is located immediately above the wrap instrument bed pinion 62. Extending vertically downwards through the central opening in the annular bearing plate 65 and right through the cylindrical wrap instrument bed 7, concentrically therewith, are concentric nested cylinders 70, 71 serving to guide the whale threads from the bobbins to the thread guiding extremities 8 of the wrap instruments 6. Near to its upper end, the complete component constituted by the nested wale thread guiding cylinders 70, 71, is rigidly connected with the annular bearing plate 65, this component being thereby adapted to be driven together with, and at the same speed as, the bobbin carrier 46.

The wrap instrument bed gear 57, the bobbin carrier gear 68 and the annular bearing plate 65 to which the latter is attached are circumferentially apertured or gapped at 73, 74 and 75 respectively to enable the wrap instruments to be extracted upwardly and loaded therethrough. The form of these apertures or gaps is depicted in FIGURES 8 and 9.

A feature of the invention resides in the provision, for use in the improved wrap striping mechanism, of a wrap instrument of the particular form illustrated in FIGURES

11

When shogging of the cylindrical wrap instrument bed 7 is to take place in a machine employing systems of selection A and B aforesaid, the method of producing a "change gap" in the system A by deliberately not selecting certain wrap instruments and thereby preventing interference between such instruments and needles 3 at the common wrap level L, is matched in the system B by leaving certain needles non-selected.

I claim:

1. A circular knitting machine comprising, in combination, a bottom plain needle cylinder, a superimposed top rib needle cylinder, a circle of double-ended latch needles for operation in said cylinders, said needles being transferable from one cylinder to the other, a cylindrical wrap instrument bed arranged concentrically within said top needle cylinder, a circular series of individually movable wrap instruments having actuating butts in said instrument bed, said instruments consisting of blade-like elements each provided with a lower thread guiding extremity extending in an axial direction with respect to the needle cylinders, means for moving said instruments radially to carry threads across the needle circle, means for producing relative movement between the thread guiding extremities and the adjacent ends of predetermined needles in the bottom needle cylinder to wrap threads around said needles and produce embroidery plating effects on the face of knitted fabric, a system of control cams for controlling movements of said wrap instruments during the wrapping of wale threads around desired needles, and means for displacing said wrap instruments lengthwise from a first height at which they are normally inoperative with their thread guiding extremities withdrawn to a second height at which the actuating butts on the instruments are acted on by said control cam system.

2. A circular knitting machine comprising, in combination, a bottom plain needle cylinder, a superimposed top rib needle cylinder, a circle of double-ended latch needles for operation in said cylinders, said needles being transferable from one cylinder to the other, a cylindrical wrap instrument bed arranged concentrically within said top needle cylinder, a circular series of individually movable wrap instruments having actuating butts in said instrument bed, said instruments consisting of blade-like elements each provided with a lower thread guiding extremity extending in an axial direction with respect to the needle cylinders, means for moving said instruments radially to carry threads across the needle circle, means for producing relative movement between the thread guiding extremities and the adjacent ends of predetermined needles in the bottom needle cylinder to wrap threads around said needles and produce embroidery plating effects on the face of knitted fabric, a system of control cams for controlling movements of said wrap instruments during the wrapping of wale threads around desired needles, means for individually displacing selected wrap instruments lengthwise from a first height at which they are normally inoperative, to a second height at which the actuating butts on the selected instruments are acted on by said control cam system so that the thread guiding extremities of selected wrap instruments only will be moved radially across the needle circle, and means for moving a succession of needles in the bottom needle cylinder to a common wrap level so that desired ones of said needles can receive wale threads from the selected wrap instruments.

3. A circular knitting machine comprising, in combination, a bottom plain needle cylinder, a superimposed top rib needle cylinder, a circle of double-ended latch needles for operation in said cylinders, said needles being transferable from one cylinder to the other, a cylindrical wrap instrument bed arranged concentrically within said top needle cylinder, a circular series of individually movable wrap instruments having actuating butts in said bed, said instruments consisting of blade-like elements each provided with a lower thread guiding extremity extend-

12

ing in axial direction with respect to the needle cylinders, means for moving said instruments radially to carry wale threads across the needle circle, means for producing relative movement between the thread guiding extremities and the adjacent ends of predetermined needles into the bottom needle cylinder to wrap threads around the said needles and produce embroidery plating effects on the face of knitted fabric, a system of control cams for controlling movements of said wrap instruments during the wrapping of wale threads around desired needles, means for displacing lengthwise all of the wrap instruments of at least one group of successive ones of said instruments from a first height at which they are normally inoperative to a second height at which the actuating butts on such displaced instruments are acted on by said control cam system, and means for selectively actuating said needles in the bottom needle cylinder and moving only selected needles of a corresponding group to a wrap level whereby only these selected needles will receive wale threads from said wrap instruments, the non-selected needles of said group remaining at another level clear of the wrap instruments.

4. A circular knitting machine comprising, in combination, a bottom plain needle cylinder, a superimposed top rib needle cylinder, a circle of double-ended latch needles for operation in said cylinders, said needles being transferable from one cylinder to the other, a cylindrical wrap instrument bed arranged concentrically within said top needle cylinder, a circular series of individually movable wrap instruments having actuating butts in said bed, said instruments consisting of blade-like elements each provided with a lower thread guiding extremity extending in an axial direction with respect to the needle cylinders, means for moving said instruments radially to carry wale threads across the needle circle, means for producing relative movement between the thread guiding extremities and the adjacent ends of predetermined needles in the bottom needle cylinder to wrap threads around said needles and produce embroidery plating effects on the face of knitted fabric, a system of control cams for controlling movements of wrap instruments during the wrapping of wale threads around desired needles, means in advance of a needle wrapping station for individually selecting the wrap instruments and displacing the selected ones lengthwise from a first height at which they are normally inoperative to a second height at which the actuating butts on the selected instruments are acted on by said control cam system so that the thread guiding extremities of selected wrap instruments only will be moved radially to and fro across the needle circle at said wrapping station, means also in advance of said wrapping station for moving a succession of needles in the bottom needle cylinder to a common wrap level so that desired ones of such needles can receive wale threads from selected wrap instruments, means in advance of another needle wrapping station for displacing lengthwise all of the wrap instruments of at least one group of successive ones of such instruments from said first height at which they are inoperative to said second height so that the thread guiding extremities of all of the instruments of said group will be moved radially across the needle circle at said last mentioned wrapping station, and means in advance of said last mentioned wrapping station for selectively actuating needles in the bottom needle cylinder and moving only selected needles of a corresponding group to the wrap level so that only these needles selected at said last mentioned wrapping station will receive wale threads from wrap instruments.

5. A circular knitting machine according to claim 2, wherein the blades of said wrap instruments are provided with fulcrum formations about which the instruments rock when being moved radially back and forth across the needle circle and triangular selecting butts of saw-tooth form disposed at different levels are formed on the upper portions of the blades extending between said ful-

crum formations and the actuating butts, said selecting and displacing means acting on the triangular butts so as to effect the required lengthwise displacement of the selected instruments.

6. A circular knitting machine according to claim 3 wherein the means for displacing said wrap instruments includes a cam of the withdrawable bolt type.

7. A circular knitting machine according to claim 1 including a horizontal leveling cam for engagement by the lower butts on said wrap instruments to determine the first height at which they are normally inoperative.

8. A circular knitting machine according to claim 4 including means at a point beyond said wrapping stations for restoring selected wrap instruments to said first height for re-selection.

9. A circular knitting machine comprising, in combination, a bottom plain needle cylinder, a super-imposed top rib needle cylinder, a circle of double-ended latch needles for operation in said cylinders, said needles being transferable from one cylinder to the other, a cylindrical wrap instrument bed arranged concentrically within said top needle cylinder, a circular series of individually movable wrap instruments having actuating butts in said bed, said instruments consisting of blade-like elements each provided with a lower thread guiding extremity extending in an axial direction with respect to the needle cylinders, means for moving said instruments radially to carry wale threads across the needle circle, means for producing relative movement between the thread guiding extremities and

the adjacent ends of predetermined needles in the bottom needle cylinder to wrap threads around said needles and produce embroidery plating effects on the face of knitted fabric, opposed inner and outer control cams at a needle wrapping station for controlling the movements of the wrap instruments during the wrapping of wale threads around desired needles, said cams being arranged in a common horizontal plane with a space between them of a width sufficient to accommodate the actuating butts on the wrap instruments, means at a selecting station preceding the needle wrapping station for raising selected wrap instruments from a first height at which they are normally inoperative to a higher level at which the instrument actuating butts enter said space, and a withdrawable neutralizing cam located beyond the wrap instrument selecting station preceding the needle wrapping station, said neutralizing cam when projected into its operative position, acting to depress predetermined raised wrap instruments to return said instruments from said higher level to said first height, whereby selection of said wrap instruments is nullified.
